Advertisements dated Sep. 20, 1989 and Jan. 20, 1998 and updated advertising materials showing a combination soap and air freshener dispenser.

Primary Examiner — David G Muller(74) *Attorney, Agent, or Firm* — KNOBBE, MARTENS, OLSON & BEAR, LLP(57) **CLAIM**

The ornamental design for an air freshener, as shown and described.

DESCRIPTION

FIG. 1 is a front, top, and side perspective view of an air freshener embodying our new design.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a back, top, and side perspective view thereof. Broken lines are used to illustrate features of the air freshener which form no part of the claimed design.
